UNITED STATES PATENT OFFICE.

AUGIE L. HANSEN, OF CHICAGO, ILLINOIS.

DESIGN FOR A SAFETY OIL-CAN.

■ 44,405.

Specification for Design.

Patented July 29, 1913.

Application filed August 2, 1912. Serial No. 713,009. Term of patent 14 years.

To all whom it may concern:

Be it known that I, AUGIE L. HANSEN, a citizen of the United States, residing in Chicago, in the county of Cook and State of Illinois, have invented a new, original, and ornamental Design for Safety Oil-Cans, of which the following is a specification, reference being had to the accompanying drawings, forming part thereof.

The figure is a side elevation of a safety oil can, showing my new design.

I claim:

The ornamental design for a safety oil can, as shown.

AUGIE L. HANSEN.

Witnesses:

C. M. BAUMEISTER,
K. DOLBEY.
